UNITED STATES PATENT OFFICE.

WILLIAM M. HENDERSON, OF HIGH SPIRE, PENNSYLVANIA, ASSIGNOR TO THE PENNSYLVANIA STEEL COMPANY, OF PHILADELPHIA, PENNSYLVANIA, A CORPORATION OF PENNSYLVANIA.

MOVABLE-POINT CROSSING.

No. 846,029.

Specification of Letters Patent.

Patented March 5, 1907.

Application filed June 26, 1906. Serial No. 323,424.

To all whom it may concern:

Be it known that I, WILLIAM M. HENDERSON, a citizen of the United States, residing in the town of High Spire, in the county of Dauphin and State of Pennsylvania, have invented certain new and useful Improvements in Movable-Point Crossings, of which the following is a full, clear, and exact description, reference being had to the accompanying drawings, of which—

Figure 1 is a plan view of a movable-point crossing, showing my invention applied thereto. Fig. 2 is an enlarged plan view showing one of the movable-point rails embodying my invention. Fig. 3 is a section on line *v v*, Fig. 2. Fig. 4 is a section on line *x x*, Fig. 2. Fig. 5 is a section on line *y y*, Fig. 2. Fig. 6 is a section on line *z z*, Fig. 2. Fig. 7 is an elevation taken on line *u u*, Fig. 1.

The object of this invention is to provide the point-rails of a movable-point crossing with a hard-metal point of unique construction and at the same time to provide said point-rails with a suitable pick-up device for guttered wheels, which pick-up device shall be integral with the hard-metal point portion.

The precise character of the invention will appear from the following description.

In the drawings, 1 designates the usual main-track rails bent to form the "knuckle" 2. 3 designates the movable rails, each of which in this instance terminates some distance to the rear of said knuckle, as seen in Figs. 1 and 2. A hard-metal point-forming piece 4 constitutes an extension of the said point-rail 3 and has extending on the outer side and to the rear end of the said point-rail an extension 5, the top of the head of which is in the same plane as the head of the point-rail, but its outer end is beveled downwardly at 6, as seen in Fig. 2. The web portion 7 of the extension 5 abuts against the web of the point-rail 3 and extends for this purpose beyond the end of said extension 5 and beneath the head of the point-rail 3, as seen in Fig. 6. The said web portion 7 is continuous with the web portion 7^a of the hard-metal point-piece in advance of the end of the point-rail. Extending from the point of said point-forming piece and lying against the web 7^a thereof throughout its length and then against the web of the point-rail 3 to a point opposite the end of the web extension 7 is a

rolled-steel strap-piece 8. Said strap-piece is secured to the web 7 of the point-forming piece by bolts 9, passing through the web 7 and through said strap-piece, as seen, and the strap 8, point-rail 3, and hard-metal piece 4 are secured together by bolts 10 passing through the strap 8, the web of the point-rail, and the web extension 7 of the said hard-metal piece, thus firmly securing the said hard-metal piece, point, and strap together. The strap-piece 8 is also provided with a foot-flange 11, to which may be attached the usual switch-bars 12, thus avoiding the attachment of said bars 12 to the hard-metal piece 4, said hard-metal piece being usually of cast metal.

By making the point portion of the point-rails 3 of hard metal the breaking down of the point under the hammer-blows of passing wheels is avoided, and by providing the head extension 5 with its beveled portion 6 on the outer side of the point-rails 3 if a wheel passing over the point-rail should be guttered—that is, have a false flange on its outer side—said false flange will ride up the inclined portion 6 onto the head extension 5, and so be uplifted to the plane of the head of the track-rails 1, over which it will pass without wearing a groove therein, as would otherwise be the case.

Having thus described my invention, I claim as new and desire to secure by Letters Patent—

1. In a movable-point crossing, the combination, with the knuckle-forming track-rail, of the movable-point rails, terminating some distance on each side of the "knuckle," the hard-metal point-forming piece, whose upper surface is in the same plane as the said point-rail, said point-forming piece having the rearward extension adjacent the outer edge of the head of the point-rail; together with means for securing said point-rail and hard-metal point-forming piece together, substantially as set forth.

2. In a movable-point crossing, the combination, with the knuckle-forming track-rail, of the movable-point rails, terminating some distance on each side of the "knuckle," the hard-metal point-forming piece whose upper surface is in the same plane as the said point-rail, said point-forming piece having the rearward extension adjacent the outer

2
edge of the head of the point-rail, and whose free rear end is downwardly beveled; together with means for securing said point-rail and hard-metal point-forming piece together, substantially as set forth.

3. In a movable-point crossing, the combination, with the knuckle-forming track-rail, of the movable-point rails, terminating some distance on each side of the "knuckle,"
10 the hard-metal point-forming piece, whose upper surface is in the same plane as the said point-rail, said point-forming piece having the rearward extension adjacent the outer edge of the head of the point-rail, and having
15 also a web portion, together with the strap-piece extending the length of the point-forming piece, its forward portion lying against the web of the latter, and its rear portion against the web of the point-rail; together
20 with the bolts securing said point-forming piece, point-rail, and strap, together, substantially as set forth.

4. In a movable-point crossing, the com-

bination, with the knuckle-forming track-rail, of the movable-point rails, terminating 25 some distance on each side of the "knuckle," the hard-metal point-forming piece, whose upper surface is in the same plane as the said point-rail, said point-forming piece having the rearward extension adjacent the outer 30 edge of the head of the point-rail, and having also a web portion together with the strap-piece extending the length of the point-forming piece, its forward portion lying against the web of the latter, and its rear portion 35 against the web of the point-rail; the foot extension of said strap-piece; together with the bolts securing said point-forming piece, point-rail, and strap together, substantially as set forth.

In testimony whereof I have hereunto affixed my signature.

WILLIAM M. HENDERSON.
